UNITED STATES PATENT OFFICE

ABRAM C. WISNER, OF JACKSON, MICHIGAN, ASSIGNOR TO REYNOLDS SPRING COMPANY, OF JACKSON, MICHIGAN, A CORPORATION OF MICHIGAN

BASE FRAME FOR SPRING-CUSHION SEATS

Application filed March 26, 1928. Serial No. 264,915.

The present invention pertains to spring cushion seats of the type used, for example, in automobiles, and is directed more particularly to the construction of the base frame which serves as the anchoring member for the springs and for the enclosing apron. Numerous devices of this general character are already known in the art, but the object of the present invention is to provide a base frame which simplifies the mode of assembly and saves time in the assembly operations.

The prior art devices generally consist of a double channel member which receives the cushion springs in one channel and the lower edge of the apron in the other channel. Usually the apron is received in the lower channel, and the result of this construction is that the springs constantly exert pressure on a portion of the apron whereby the latter is likely to become weakened and worn. The interposition of the apron-receiving channel between the supporting structure and the spring-receiving channel further adds to the height of the cushion. Added height of such parts in automobile construction is objectionable inasmuch as it is desired to retain as much head room as possible, consistent with the present custom which favors low top vehicles.

These objections are overcome in the present invention by securing the springs in the lower channel and anchoring the lower edge of the apron in the upper channel. It will readily be apparent that this arrangement avoids the added height of the seat and the strain on the lower part of the apron occasioned by anchoring the apron below the springs.

Further objects and advantages of the invention will appear as the description proceeds in accordance with the accompanying drawings which illustrate one embodiment of the invention, and wherein—

Figure 1 is a perspective view, partly broken away, of a spring cushion seat constructed according to the invention;

Figure 2 is a detail vertical section thereof;

Figure 3 is a fragmentary plan view of the base frame;

Figure 4 is a fragmentary perspective view of the base frame;

Figure 5 is a fragmentary perspective view of the lower part of the apron; and

Figure 6 is a cross section of the base frame.

Reference to these views will now be made by use of like characters which are employed to designate corresponding parts throughout.

The base frame is a metallic member having the contour of the lower edge of the seat and bent to form an inwardly facing channel 1 and an outwardly facing channel 2. The member thus bent has the appearance of a reversed S in cross section as viewed in the several figures, although it would be of obverse S-shape if viewed in the opposite direction.

The lower wall 3 of the lower channel 1 is flat in order to provide a flat bearing upon the supporting surface as will presently appear, while the upper wall 4 of the upper channel 2 is sloped downwardly to form a comparatively restricted mouth for a purpose presently to be described. The free edge of the wall 4 is rounded or bent back upon itself as at 5 in order to avoid cutting or severing the fabric which comes into engagement therewith.

The usual helical springs 6 confined within the base frame have their lower coils received in the lower channel 1 as illustrated more clearly in Figures 2 and 3. The lower wall 3 is hammered up as at 7 at the points of tangency, whereby the springs are positively secured in the base frame. A pad or cushion 8 of upholstery material is laid upon the springs 6, and an apron 9 of suitable fabric hangs from the pad in a manner to enclose the spring structure. The apron may be associated with the pad in any desired manner, but is here illustrated as having its upper edge 10 secured to the base of the pad and fitted between this base and the upper coils of the springs 6.

The lower edge of the apron is folded upon itself as at 11 in order to enclose a welt cord 12 which is retained by stitching 13 along the doubled part of the apron.

For the purpose of securing the lower edge of the apron in the base frame, the cushion is compressed in a suitable machine in order that the apron may be sufficiently slack, with

respect to the base frame, to permit manipulation of the lower edge thereof.

The welted edge is inserted in the upper channel 2 through the outwardly facing and restricted mouth thereof. A locking member 14, such as a fiber cord, wood cord or wire cord, is also inserted in the upper channel and is retained by the spring action which results from the further restriction of the mouth of the channel by the juxtaposition of the doubled part of the apron against the upper wall of the channel. The usual operation of pinching the channel by means of a tool in order to hold the lower edge of the apron is thus avoided. It will also be seen that the sharp edge of the channel is removed from the apron, due to the bend 5, so that the apron cannot be cut in this region.

The above mentioned advantages of the invention will now be apparent. Due to the fact that the springs 6 are received in the lower channel, there is provided a flat metal bearing upon the supporting surface. The anchoring of the lower end of the apron above the base of the springs prevents the apron from being compressed beneath the springs and further reduces the height of the cushion by the width of the welt-receiving channel.

Although a specific embodiment of the invention has been illustrated and described, it will be understood that various alterations in the details of construction may be made without departing from the scope of the invention as indicated by the appended claims.

What I claim is:—

1. In an upholstery construction, a base frame consisting of a double channel member, one channel being above the other, cushion springs secured in the lower channel, upholstery material mounted upon said springs, an apron depending from said material and enclosing said springs, a welt cord attached to the lower edge of said apron and received in said upper channel, and a locking member sprung in said upper channel for retaining said welt cord.

2. In an upholstery construction, a base frame consisting of a double channel member having an inwardly facing channel and an outwardly facing channel, cushion springs secured in the inwardly facing channel, upholstery material mounted upon said springs, an apron depending from said material and enclosing said springs, a welt cord secured to the lower edge of said apron and received in said outwardly facing channel, and a locking member sprung in said outwardly facing channel for retaining said welt cord.

3. In an upholstery construction, a base frame consisting of a double channel member having an upper outwardly facing channel and a lower inwardly facing channel, cushion springs secured in the lower channel, upholstery material mounted on said springs, an apron hanging from said material and en-

closing said springs, a welt cord secured to the lower edge of said apron and received in said upper channel, and a locking member sprung in said upper channel for retaining said welt cord.

4. In an upholstery construction, a base frame consisting of a double channel member, one channel being above the other, a cushion spring structure secured in the lower channel, upholstery material mounted upon said spring structure, an apron depending from said material and enclosing said spring structure, a welt cord attached to the lower edge of said apron and received in said upper channel, and a locking member sprung in said upper channel for retaining said welt cord.

In testimony whereof I affix my signature.

ABRAM C. WISNER.
